TEMPLATE FOR LOCK MORTISES

Robert R. Josephson, Costa Mesa, Calif., assignor,
by direct and mesne assignments, to Kwikset
Locks, Inc., Anaheim, Calif., a corporation of
California

Application August 5, 1950, Serial No. 177,921

10 Claims. (Cl. 33—197)

1

This invention relates to a template for guiding a wood-cutting tool and, more particularly, relates to a template for use in routing mortises in doors and door jambs preliminarily to the installation of locks and striker plates.

It is an object of this invention to provide a template which with simple adjustment may be used as a guide for a routing tool in either of the operations of routing a door for a lock or latch mechanism or of routing a door jamb for a bolt recess and striker plate.

A further object of the invention is to provide a template adjustable to work on doors of different thicknesses, for example, on an outer door for which the standard thickness is usually one and three-quarters inches or an inside door having a thickness of one and three-eighths inches by ordinary standards. By this provision, it will be seen that one template may readily serve for mortising all the doors and jambs in the ordinary house, and greatly simplify and shorten the operation of installing door hardware.

In large scale housing construction, such as a real estate sub-division in which ready built houses are offered for sale, a general contractor usually provides hardware of one style or make, and one template embodying my invention and of suitable style may be used throughout the sub-division on successive houses. However, a contractor building houses to individual specifications may have to install various types of door locks, and for that purpose I have provided a template constructed to permit alteration of the routing pattern and depth by substitution of small parts and inserts.

Another object, achieved in the same manner as the foregoing, is to provide a template in which the parts immediately defining the routing pattern may be readily replaced if gouged or buried by the routing tool, thus saving the major portion of the template.

In general terms I achieve the above objects of my invention and others which will be pointed out or be apparent as the following description of a preferred embodiment of my invention proceeds, by forming a template body having a T-shaped opening for guiding a routing tool, in which the head of the T represents the area to be routed in forming the recess in the door to receive the lock mechanism and the recess in the jamb to receive the extended bolt or latch, and the stem of the T represents the additional area to be routed in the jamb to receive the tongue of the striker plate. A sliding gate is arranged to

2

cut off the T-stem part of the opening when the template is used on a door. A depth plate is provided, conveniently hinged at one side of the template and having a like T-shaped opening, which may be swung into position over the template body to increase the thickness of the template and thereby reduce the depth of the cut in a door jamb. The face of the template which is to engage the work has spikes or spurs by which the template may be temporarily secured to the woodwork, and gage arms are pivotally secured to both ends of the template, to be swung into position to posit the template with relation to an edge of the woodwork as the thickness of the door may require.

In the accompanying drawings, illustrative of a preferred embodiment of my invention:

Fig. 1 shows a template having the depth plate swung back to expose the inner surface of the template body;

Fig. 2 is a fragmentary view similar to Fig. 1, in which the plates forming the inner surface of the template body have been removed to permit observation of the sliding gate and other details;

Fig. 3 is an edge view in perspective, showing the manner of applying the template to the edge of a door;

Fig. 4 shows the template with the depth plate folded over the template body, the tool being applied to a door jamb;

Fig. 5 is a sectional view on the plane of section indicated by the line 5—5 of Fig. 1, and greatly enlarged, showing one of the spurs by which the template is secured to wood-work;

Fig. 6 is another enlarged sectional view on the plane of section indicated by the line 6—6 of Fig. 1, showing one of the gage arms for positng the template on a door;

Fig. 7 is an enlarged detail in plan of the control mechanism of the sliding gate, cooperating parts being shown as if layed out for assembly with normally contiguous surfaces exposed to view; and

Fig. 8 is an enlarged sectional view of the control mechanism of the sliding gate, the plane of section being indicated by the line 8—8 of Fig. 1.

Having reference now to the details of the drawings, I have shown a template comprising a body 10, which in its preferred form is built up in three layers, and a depth plate 11 hinged to one margin of the body. The lower layer of the body 10, appearing uncovered in portions of Fig. 2 and in profile in Fig. 3, is a face plate 12 having a flat outer face suitable for application to a plane surface of woodwork. At the margin

opposite to the hinges 13 is a rectangular opening 14 having its greatest length parallel to said margin and having a small rectangular extension 15 extending toward the hinged margin. The openings 14 and 15 have the configuration of the conventional striker plate and are made large enough to define the mortise required to set the largest striker plate which is likely to be used in conjunction with the particular template. The opening 15 represents the area to be mortised for the tongue of such striker plate.

The intermediate layer of the body 10, shown in Fig. 2, comprises two L-shaped plates 17, and two bars 18. The plates 17 extend from the ends of the face plate 12 to the opening 14 and from the distal margin of the face plate 12 to the hinges 13. The plates of the hinges 13 which are secured to the plate 12 lie in the plane of the intermediate layer and may be considered parts thereof. The bars 18 extend along the hinged margin of the plate 12 convergently from the hinges 13 and are spaced by a gap 19. The space between the plates 17 and the bars 18 forms a guideway 20 upon the plate 12, in which is a gate 21, arranged for sliding movement parallel to the bars 18. The gate 21 has an opening 22, which at one end of the movement of the gate will register with the opening 15, and it is manipulated by a handle 23 which extends through the gap 19. The gate 21 has the same thickness as the plates 17 and bars 18 and lies in their plane.

The inner layer of the body 10, shown exposed in Fig. 1, has end plates 25, preferably notched to expose the plates of the hinges 13, to permit removal of the hinges, and a center plate 26 which has an opening 27 and an extension opening 28 registering with the openings 14 and 15 of the plate 12.

The fixed elements of the three layers of the body 10 are held together by screws 30, the plates 25 being thus secured to the plates 17 and to the face plate 12, and the plate 26 being secured to the plates 17 and bars 18 and thence to the plate 12.

The outer edge of the opening through the body 10 formed by the registering openings 14 and 27 and the gap between the plates 17 is closed by a bar 32, inlaid in suitable notches in the plates 12, 17, and 26 and secured by screws 33 to the plates 17. It will be observed that this general opening is bounded in the planes of the intermediate and inner layers by the relatively small individual plates 17 and 26, by the gate 21, and by the bar 32. It is at these levels that damage by a routing tool is most apt to occur, and the construction comprising separable layers, each made of small parts, makes possible economical and easily effected repairs. Furthermore, since only the opening 14-15 in the face plate 12 is bounded by fixed boundaries and as these boundaries are usually below the level of the guide of a routing tool, the size and shape of the general opening may be controlled within the limits of the opening 14-15 by substitution of differently shaped elements for the plates 17 and 26 and the gate 21. The plates 17 and 26 and the gate 21 may be considered as inserts for which substitution may be made either to effect repairs or to control the size and shape of the general opening.

The depth plate 11 also has an opening 35 corresponding to and registering with the opening 14-15 as closed by the bar 32. When the depth plate is folded over the body 10, making a four-

layer template, the opening 35 will, like the opening 14-15, control the maximum size of the general opening, but the routing tool will be guided by the margins of the openings in the central layers. The depth plate 11 also has a notch 36 in its proximal margin, disposed to register with the handle 23 of the gate 21 when the gate is in position to close the opening 15. The length of the handle 23 and the free space between the body 10 and the depth plate 11 as provided by the hinges 13, are such that the handle 23 will engage the proximal margin of the depth plate at all positions other than the notch 36 when the depth plate is opened to the plane of the body 10 as shown in Figs. 1 and 2. This construction prevents the opening of the depth plate to the position indicated except when the gate 21 closes the opening 15.

To hold the gate 21 at either limit of its traverse in the guideway 20, the handle 23 is provided with a spring latch 38, illustrated in Fig. 8. Grooves 39 in the plate 26 extend from the opening 28 to the adjacent margin of the plate, to receive and hold the latch 38 at its limit positions, as shown in Fig. 7, it being understood as heretofore stated that the plate 26 is therein shown as if detached from the bars 18 and turned over and that the grooves 39 will engage the shown surface of the latch 38.

In order to affix the template to woodwork, spurs 40 are provided. These spurs are sharpened screws which pass freely through suitable holes in the plates 25 and 17 and are threaded in the face plate 12, from the working surface of which their sharp points extend. It will be seen that their degree of penetration into woodwork is adjustable, and that when worn they may be removed for sharpening. They also serve, in combination with the screws 30, to hold the plates 25 and 17 in orientation.

However, before the template is affixed to a door or a jamb by the spurs 40, it must be accurately placed relatively to the striker edge of the door or to the stop of the jamb. For this purpose, gage arms are provided at each end of the template. To place the template relatively to a door, a plurality of gage arms 42 may be mounted in individual slots 43 in the end margins of the body 12, and pivoted on pins 44 mounted in the plates 17 so as to swing to positions normal to the working face of the face plate 12. The gage arms 42 are sufficiently long to extend beyond the spurs 40 when they are normal to the plate 12 so that they may engage the side of a door while the spurs are merely pressed against the door edge without penetrating it. The arms 42 may be spaced according to different thickness of doors which may be encountered: for example, two arms would be spaced apart one-half the difference in thickness of inside doors and outside doors to maintain the mortises in relative positions, and the arm nearest the proximal margin of the body 10 would be placed normal to the face plate 12 when placed upon the thicker door, the other arm being then left in extension of the template.

For the same purpose jamb gage arms 46 are placed at the distal corners of the body 10, being pivotally mounted in corner notches 47 in the plates 17 on pins held in the plates 12 and 25, so as to swing in a plane parallel to the face of the plate 12. When in positions normal to the distal margins of the body 10, the arms 46 will extend beyond these margins a distance of one-half the

difference in thickness of two different doors, being placed in this normal position for placing the template on jambs of the greater thickness, as shown in Fig. 4, and being extended above and below the template when operating on the thinner jambs.

In operation the template is always gaged from the striking side of a door and from the struck side of a jamb. The proper size and shape of the general opening through the body 10 having been established either as shown or by substitution of inserts as described, to cut a door mortise the template is placed upon the door edge, with corresponding pairs of gage arms 42 pressed against the striking side of the door. The spurs 40 are pressed into the woodwork, the gate 21 is moved into position to close the openings 15-28, and the depth plate 11 is folded back to the plane of the body 10. A routing tool may then be applied to the template, with the cutter extending through the remaining open portion of the general opening, the guide of the tool engaging the sides of the open portion, and the face of the tool pressed against the plate 26. The mortise may also, of course, be cut with a chisel guided in the same manner.

The jamb mortise is cut in the same way, positioning the template with reference to the jamb stop either by the distal margin of the body 10 or by the gage arms 46 as may be required, and by pressing the spurs 40 into the woodwork. The gate 21 is moved to uncover the openings 15-28, and the depth plate 11 is folded upon the body 10. A routing tool may then be applied to the outer face of the depth plate 11, and will rout a shallow mortise differing in depth from the door mortise by the thickness of the plate 11 and suitable for a striker plate instead of the relatively heavier lock plate.

I wish it understood that the embodiment of my invention herein described and illustrated is an example of a complete and workable template within the scope and spirit of my invention, that scope being defined in the appended claims, within which changes of arrangement and construction may be made without departure from the spirit of the invention.

I claim:

1. A template for use in cutting lock mortises in doors and door jambs, comprising: a body having a surface adapted for application to the work, and having an opening extending through said body to said surface; a depth plate hinged to a margin of said body so as to swing flatly against the opposite surface of said body to increase the effective thickness of said template and having an opening co-extensive with and registering with the opening in said body; a gate for closing a portion of said body opening; and spurs on said first-mentioned surface of said body adapted to penetrate woodwork for attaching said template thereto.

2. A template for use in cutting lock mortises in doors and door jambs, comprising: a body having a surface adapted for application to the work and having an opening extending through said body to said surface and in shape representative of a jamb mortise inclusive of the area of a striker tongue; a depth plate hinged to said body and applicable to the opposite surface of said body and having an opening co-extensive with and registering with the opening in said body; a gate for closing the portion of the opening in said body representative of the striker tongue area; and means on said gate engageable with said

depth plate when said gate is open for then preventing said depth plate from swinging away from said opposite surface of said body.

3. A template for use in cutting lock mortises in doors and door jambs, comprising: a body having a surface adapted for application to the work, and having an opening extending through said body to said surface; a depth plate applicable to the opposite surface of said body and having an opening registering with the opening in said body; a gate for closing a portion of said body opening; gage arms at the ends of said body pivotable between positions in which they may abut surfaces of the work angulated with respect to the work surface to which said body is applied for positioning said body relatively to said angulated surfaces and positions in which they are retracted from abutment with said angulated surfaces.

4. A template as described in claim 3, in which said gage arms include arms pivotable in planes parallel to the plane of said body surface.

5. A template as described in claim 3, in which said gage arms include a plurality of arms at each end of said body pivotable between positions in which they are normal to said body surface and positions in which they are in prolongation of said body.

6. A template for use in cutting lock mortises in doors and door jambs, comprising: a body having a surface adapted for application to the work, and having an opening extending through said body to said surface; and a depth plate hinged to said body so as to be applicable to the opposite surface of said body and having an opening registering with the opening in said body.

7. A template for use in cutting lock mortises in doors and door jambs, comprising: a body having a surface adapted for application to the work, and having an opening extending through said body to said surface; gage arms at the ends of said body extendable normally to said body surface so as to abut portions of the work for placing said template with reference to the work; and spurs on said body surface for securing said template to the work, said gage arms having greater effective length than said spurs whereby said template may be placed in desired position prior to being secured to the work.

8. A template for use in cutting lock mortises in doors and door jambs, comprising: a body having a plurality of layers, inclusive of a face plate having a surface adapted to be applied to woodwork, and a plurality of insert plates superimposed on said face plate; said face plate having an opening extending therethrough to said surface; and said insert plates being removably mounted on said face plate so as to define an opening registering with the opening in said face plate and to be capable of substitution and replacement whereby a general opening within the limits of said face plate opening may be formed in said body; and a depth plate hinged to said face plate so as to cover said insert plates and to increase the effective thickness of said template when in covering position, and having an opening coextensive with said face plate opening and registering therewith.

9. A template for use in cutting lock mortises in doors and door jambs, comprising: a body inclusive of a face plate having a surface adapted to be applied to woodwork, and a plurality of additional plates superimposed on said face plate and arranged in at least two layers; said face plate having an opening extending therethrough to said surface and in shape representative of a

jamb mortise inclusive of the area of a striker tongue; said additional plates being arranged to define an opening registering with the opening in said face plate and a guideway traversing the portion of said openings representative of the striker tongue area; and a gate slideable in said guideway to close said portion of said openings, said guideway being closed by one of said layers to retain said gate in said guideway.

10. A template for use in cutting lock mortises in doors and door jambs, comprising: a body having a surface adapted for application to wood-work and having an opening extending through said body to said surface; a depth plate hinged to a margin of said body so as to swing flatly against the opposite surface of said body and having an opening co-extensive with and registering with the opening in said body; a guideway within said body traversing a portion of said registered openings adjacent to the hinged margin of said body; a gate slideable in said guideway for

closing said portion of said openings; a handle on said gate extending beyond the hinged margin of said body; the hinged margin of said depth plate extending into the zone of movement of said handle so as to prevent said depth plate from swinging open from said body by the interference of said handle with said margin, and having a notch registering with the position of said handle when said gate is closed to then, and then only, 10 permit said depth plate to be swung fully away from said body.
